(57) **CLAIM**

The ornamental design for a multiuse mount as shown and described.

DESCRIPTION

FIG. 1 is a rear perspective view of a multiuse mount showing our new design in a first position of use;

FIG. 2 is a front perspective view thereof;

FIG. 3 is a rear elevational view thereof;

FIG. 4 is a front elevational view thereof;

FIG. 5 is a bottom plan view thereof;

FIG. 6 is a top plan view thereof;

FIG. 7 is a rear perspective view of the multiuse mount of FIG. 1, shown in a second position of use;

FIG. 8 is a front perspective view thereof;

FIG. 9 is a rear elevational view thereof;

FIG. 10 is a front elevational view thereof;

FIG. 11 is a bottom plan view thereof; and,

FIG. 12 is a top plan view thereof.

Broken lines illustrate portions of the multiuse mount that form no part of the claimed design.
